Gustav Hanssen

UNITED STATES PATENT OFFICE.

GUSTAV HANSEN, OF ST. LOUIS, MISSOURI.

FOLDING AND EXTENSION TRESTLE.

SPECIFICATION forming part of Letters Patent No. 318,896, dated May 26, 1885.

Application filed February 12, 1885. (No model.)

To all whom it may concern:

Be it known that I, GUSTAV HANSEN, a citizen of the United States, residing at 1302 Arsenal street, in the city of St. Louis, in the State of Missouri, have invented a new and useful Folding and Extension Trestle, of which the following is a specification.

My invention relates to a trestle which can be easily folded for transportation or storage, quickly adjusted for use, and easily extended. These objects I attain by the mechanism demonstrated by the annexed drawings.

Figure I is a cross-section of the upper part of the trestle. *a* indicates the casting into which the trestle-beam *o* is placed. It, *a*, has on each side a socket or inlet, into which the castings *b* and *b* (the ends of the trestle-supporters *c* and *c*) are forced and held in position by the bolts or fasteners *d* and *d*, *d* and *d* each running through a trestle-supporter, *c* or *c*, and maintaining or holding both *b* and *b* and *c* and *c* in position. *e* acts as center bolt and fastener, holding the whole together, and is also the pivot or axle on which the legs *c* and *c* move when being adjusted.

Fig. II shows the end view of the trestle in position, the supporters *c* and *c*, with ends of *b* and *b* in sockets of *a*, maintained by the center bolt, *e*, the opening of the hinge-brace *f*, the extension *g* and *g* and *c* and *c* controlled, regulated, or maintained by the sliding clamps *h* and *h* in connection with the clamp-sockets *p* and *p*, together with the clamps *i* and *i*, and adjusted by the brakes *j* and *j*.

Fig. III represents the side view, demonstrating by the arrows *k* and *l* and *m* and *n* how the trestle may be folded or unfolded after the adjustment of the hinge-brace *f* for ready use, storage, or transportation, as exhibited in Fig. IV.

The trestle can be constructed of different materials. *a*, *b*, *f*, and *j* can be constructed of cast or other iron; *d*, *e*, *h*, *i*, and *g* of wrought-iron; *c*, *g*, and *o* of wood or iron. The whole may be constructed of any size to suit.

a is a casting longer than wide—in this case six inches long by two and one-half wide by four and one-fourth high—with a tubular socket for the bolt or axle *e*. It is also formed with a cut or notch two by four and six inches long for the beam *o*, and two half-inch holes

at the ends of the bottom to insert bolts *q* *q*, which fasten the beam to *a*, with projections *r* and *r*, of three-eighths of an inch on each side, forming the inlets for the shoes *b* and *b*.

b and *b* are longer cast-shoes of beveled shape at the upper end, three inches wide, (which fit into inlets formed by *r* and *r*), into which *c* and *c*, the supports or legs, are inserted and fastened by bolts *d* *d*, having been first secured by means of the axle-bolt *e* to *a*. This securing is accomplished by inserting *b* and *b* on each side of *a* onto the ends of the axle *e*, then riveting the ends of *e* in such a manner that *b* and *b* have some play on *e* sufficient to enable the folding and unfolding and securing of the trestle.

c and *c* are supports, and must correspond in length to the height of the trestle desired, (are in this description two by three inches,) with notches *p* *p* for *h* and *h* to anchor into at regular intervals, upper end to fit closely into the shoes *b* and *b*, held in position by bolt *d*.

d and *d* are nut-bolts inserted below *a* through *b* and *b* and *c* and *c*, and holding them together, as already explained.

e is an axle, the body of which is firmly embedded in *a* below the notch for *o*, the ends of *e* projecting and forming axles, onto which shoes *b* and *b* are placed, and the ends of *e* are then riveted, so as to hold *b* and *b* with play, as stated.

f is a hinge-brace (joint) fastened to the lower ends of *c* and *c*, the opening of which forces *b* and *b* against rivets of *e* and into the inlets formed by *r* and *r*, securing two firm supports. The closing of the brace enables the folding by bringing about the reverse action.

g and *g* are the outer supports or additions to the supports *c* and *c*, enabling the easy extension of the trestle. They are of the same shape and dimension of *c* and *c*, are held and moved up and down the outer sides of *c* and *c*, regulated by the clamps *h* and *h* fastened to their upper ends, and are held in the designed position by means of *h* and *h* anchoring into the sockets *p* and *p* in *c* and *c* and by the closing of the brakes *j* and *j*.

i and *i* are two clamps held to the lower ends of *c* and *c* by the same fastenings as *f*, and in which *g* and *g* slide up and down when the trestle is extended or shortened.

j and *j* are two cam-shaped brakes with

handles, attached to the clamps *i* and *i*. When the handle is turned upward, they permit *g* or *g* to slide up or down *c c*. When the handle is turned downward, *g* or *g* is held firmly 5 to *c* or *c*.

k and *l* and *m* and *n* on the drawings are arrows, showing the motion of the supports *g g* and *c c* in opening and folding the trestle.

o is the beam of the trestle, in the drawings 10 two by four inches, length to suit, the ends of which are inserted into the notch of the casting *a*, and held in position by two nut-bolts, *q* and *q*, at each end, running through it, and *a* in each notch of *a*.

15 *p* and *p* are sockets cut into the supports *c* and *c* sufficient to catch and anchor *h* and *h*.

q are four bolts holding *o* at each end in the notch of *a*, as described, size to suit *o* and notch in *a*, as the same may be cast.

20 *r* and *r* are projections cast onto the outside of *a* near the upper edge, and on each side forming inlets, corresponding in width to *b* and *b*, answering the double purpose of supporting and preventing swaying of the trestle in connection with *j*, as described.

As will be seen by the above, the trestle is folded by first closing *f* in each of the supports. This draws *c g* and *c g* toward each other, and at the same time draws the shoes *b b* out of the

25 inlets formed by *rr*. The legs can then be swung on the axle *e*. One pair of the supports is then

moved inward and up (*m* and *n* in Fig. III) to the beam *o*, the other outward and over (*k* and *l* in Fig. III) onto the beam *o*, when the trestle is folded as in Fig. IV. The trestle is lowered 35 by opening the brakes *j* and *j* and raising the clamps *h* and *h* out of the sockets *p p*, then sliding *g* and *g* up along *c* and *c*; is raised by the reverse motion of *g* and *g* along *c* and *c*. When *h* and *h* are anchored in *p* and *p* and *j* and *j* 40 closed, as herein described, the trestle will then maintain its height.

I am aware that possibly some of the parts have been used independently; but

I claim—

1. The combination of the casting *a* and the shoes *b b* with the bolts *d d* and axle *e*, whereby said shoes are capable of a lateral movement to and from said shoes and also a swinging movement to permit them to be folded 50 compactly.

2. In combination with the notched legs *c* and plain legs *g*, the clamps *h* and *i* and cam-lever *j*, substantially as described and set forth.

3. The combination of the casting *a*, shoes *b*, 55 bolts *d*, axle *e*, beam *o*, legs *c*, and brace *f*, substantially as shown and described.

GUSTAV HANSSEN.
